[57] **CLAIM**

The ornamental design for a bag holder, as shown and described.

DESCRIPTION

FIG. 1 is a left end, top and front perspective view of a bag holder showing my new design;

FIG. 2 is a left end elevational view thereof, the opposite end being a mirror image;

FIG. 3 is a front elevational view thereof;

FIG. 4 is a rear elevational view thereof;

FIG. 5 is a top plan view thereof;

FIG. 6 is a bottom plan view thereof;

FIG. 7 is a left end, top and front perspective view of a bag holder showing another embodiment of my new design;

FIG. 8 is a left end elevational view of FIG. 7, the opposite end being a mirror image;

FIG. 9 is a front elevational view of FIG. 7;

FIG. 10 is a rear elevational view of FIG. 7;

FIG. 11 is a top plan view of FIG. 7; and,

FIG. 12 is a bottom plan view of FIG. 7.
